CLAIM

The ornamental design for a facial massage tool, as shown and described.

DESCRIPTION

FIG. 1 is a top isometric view of a first embodiment of the facial massage tool, showing our new design;

FIG. 2 is a right view thereof;

FIG. 3 is a left view thereof;

FIG. 4 is a front view thereof;

FIG. 5 is a rear view thereof;

FIG. 6 is a top side view thereof;

FIG. 7 is a bottom side view thereof;

FIG. 8 is a bottom isometric view of thereof;

FIG. 9 is a top isometric view of another embodiment of the facial massage tool;

FIG. 10 is a right view thereof;

FIG. 11 is a left view thereof;

FIG. 12 is a front view thereof;

FIG. 13 is a rear view thereof;

FIG. 14 is a top side view thereof;

FIG. 15 is a bottom side view thereof; and,

FIG. 16 is a bottom isometric view of thereof.

The evenly spaced dashed lines in the Figures depict portions of the facial massage tool that form no part of the claimed design.

1 Claim, 14 Drawing Sheets
